UNITED STATES PATENT OFFICE.

EUGEN ZBINDEN, OF BERN, SWITZERLAND, ASSIGNOR TO SULZER FRÈRES SOCIÉTÉ ANONYME, A CORPORATION OF SWITZERLAND.

LOCOMOTIVE HAVING COMBINED INTERNAL-COMBUSTION AND ELECTRIC PROPULSION SYSTEM.

Application filed December 5, 1924. Serial No. 754,033.

To all whom it may concern:

Be it known that I, EUGEN ZBINDEN, a citizen of Switzerland, residing at Bern, Switzerland, Beundenfeldstrasse 32, have

5 invented certain new and useful Improvements in or Relating to Locomotives Having Combined Internal-Combustion and Electric Propulsion Systems, of which the following is a specification.

10 This invention relates to locomotives having combined internal combustion and electric propulsion systems, and has for its object to provide a locomotive having the generator placed as low in the frame as possible.

According to this invention the generator is mounted in the frame of the locomotive between two bogies and is driven by two internal combustion engines arranged at 20 each end thereof. The generator shaft may be directly coupled to those of the internal combustion engines, in which case separate bearings are unnecessary or these may be provided if desired.

25 Three constructions according to the invention are illustrated by way of example in the accompanying drawing, in which

Fig. 1 is a diagrammatic side elevation of a locomotive constructed in accordance 30 with the invention, and

Fig. 2 is a diagrammatic side elevation of a modification.

On the bogies *a* having driving wheels *b* is mounted by means of pivot pins a frame 35 *c* which connects the bogies together and forms a support for the superstructure of the locomotive together with its power unit.

The latter comprises an electric generator *d* arranged between the bogies and coupled 40 at each end to an internal combustion engine *e* conveniently disposed over the bogies. As the generator is the part of the power unit which projects downwards to the greatest extent, its arrangement above the free

45 space between the bogies will enable it, together with the internal combustion engines, to be arranged at a lower level above the rails than hitherto.

This result is secured by dividing the prime mover into two units, the bed plates 50 of which have a smaller depth than that of a single engine of double the power.

Such an arrangement of the generator and internal combustion engines has the additional advantage that it is possible to connect the generator shaft, shown in Figure 1 to the shafts of the internal combustion engines in such a manner as to render superfluous any separate bearings for the generator shaft. In certain cases it may 60 nevertheless be preferable to provide the latter with bearings as shown in Figure 2.

Having now particularly described and ascertained the nature of our said invention and in what manner the same is to be performed we declare that what we claim is:—

1. In an electrically propelled internal combustion locomotive the combination of two bogies with an electric generator supported by the frame of the locomotive between the two bogies and driven by two internal combustion engines arranged at either end thereof.

2. In an electrically propelled internal combustion locomotive the combination of two bogies with an electric generator supported by the frame of the locomotive between the two bogies and driven by two internal combustion engines arranged at either end thereof, the generator being let 70 into the vehicle frame supporting the internal combustion engines.

3. In an electrically propelled internal combustion locomotive the combination of two bogies with an electric generator supported by the frame of the locomotive between the two bogies and driven by two internal combustion engines arranged at either end thereof, the shaft of the generator being supported by the shaft ends of the 85 internal combustion engines without bearings of its own.

In testimony whereof I have affixed my signature.

EUGEN ZBINDEN.
